IRONING MACHINE

John A. Castricone, Peoria, Ill.

Application November 9, 1932, Serial No. 641,835

3 Claims. (Cl. 38—61)

The ironer to be described is of the power driven, roller type, the general arrangement consisting of a roller contacted by a movable ironing shoe, the said roller being supported upon a member extending from the frame of the head mechanism, which is in turn suitably attached to and supported by a bench or table 61, as clearly shown in Figs. 1 and 2 of the accompanying drawings.

Power for driving the several elements is furnished by a conventional motor through mechanism and controls to be described, the whole forming a complete working unit.

The main object of the invention is to provide a power driven ironer of the roll type which is particularly suited to domestic use.

Another object is to provide an ironer which may be efficiently operated by inexperienced persons with a minimum of physical effort.

A further object is to provide an ironer having an independently controlled power driven roller and an independently controlled power operated ironing shoe adapted to be placed in contact with or withdrawn from the roller.

Another object is to provide a power operated shoe which is automatically withdrawn from contact with the roller when rotation of the roller is discontinued.

A still further object is to provide an ironing shoe which when placed in contact with the roller by the operated power means, may be removed from such contact by manual means without disturbance of the power operated means.

Other and further objects will appear in the accompanying description and drawings, in which—

Fig. 1 is an end elevation of the ironer as it might appear in commercial form;

Fig. 2 is a side elevation as viewed from the rear of the ironer;

Fig. 3 is an enlarged end elevation with housing cover removed and several parts broken away to admit clearer view;

Fig. 4 is a sectional view taken in the direction of the arrows on line 4—4 of Fig. 3, with certain parts removed to admit clearer view, and eccentric rotated one quarter turn to facilitate description;

Fig. 5 is a view taken in the direction of the arrows on line 5—5 in Fig. 4, with several parts removed to admit clearer view;

Fig. 6 is a view taken in the direction of the arrows on line 6—6 in Fig. 4, with several parts removed to admit clearer view of underlying parts.

Fig. 7 is a sectional view taken in the direction of the arrows on line 7—7 of Fig. 3;

Fig. 8 is a detail sectional view of the roller drive clutch mechanism to be described;

Fig. 9 is a detail sectional view of the oil pump to be described;

Fig. 10 is a perspective view of the roller clutch 5 operating key to be described;

Fig. 11 is an enlarged elevational view, taken in the direction of the arrows on line 11—11 in Fig. 4, showing the ironing shoe operating clutch in engaged position;

Fig. 12 is a view similar to Fig. 11, showing the clutch in disengaged position;

Fig. 13 is a sectional view taken in the direction of the arrows on line 13—13 of Fig. 2, showing the ironing shoe in working position;

Fig. 14 is a view similar to Fig. 13, with the ironing shoe in non-working position;

Fig. 15 is a view of the ironing shoe supporting and operating members as viewed from the side opposite to that shown in Fig. 2, with shoe and portions of bracket removed to admit clearer view, (see Fig. 14); and

Fig. 16 is a detail view taken in the direction of the arrows on line 16—16 of Fig. 3.

As already mentioned, the ironing roller is 25 power driven, the source of power being a conventional electric motor located within the housing projection 1 clearly shown in Figs. 1 and 2. The motor being of standard manufacture, will not be further described.

The end of the motor shaft projects into the mechanism housing 16 and is adapted to rotate the worm shaft 3 through a conventional toothed coupling 2, as clearly shown.

Shaft 3 is rotatably mounted in bearing supports 4, the same being integral with frame member 15. The motor end support is fitted with a shouldered bushing 5, the opposite end with a bushing 6 of elongated form adapted to form a bearing for the end of shaft 3 and also support a thrust ball 7 and adjustment screw 8 with lock nut 9. The functions of the several parts will be obvious after observation of the sectional view in Fig. 5.

Integral with shaft 3 is a worm 10 adapted to 45 mesh with worm gear 11, as shown in Fig. 5. Worm gear 11 is fixedly mounted upon a sleeve member 12 disposed at right angles with shaft 3, as shown in Fig. 7. To said sleeve member 12 is also fixedly mounted a spur gear 13 and an internal gear 19, each of which will be referred to later.

The left hand end of the sleeve 12, as viewed in section in Fig. 7, is rotatably mounted in a bushing 14 which is supported by frame member 55

15, the latter being attached to suitable projections from housing 16, all as clearly shown in Fig. 7.

5 Rotatably and slidably mounted within sleeve 12 is a shaft 17 on the left hand end of which, as viewed in Fig. 7, is fixedly mounted a spur pinion 18. It will be apparent that shaft 17 is supported, at the left hand end, by and within sleeve 12, while the right hand end is rotatably and slidably mounted in bushing 18', which latter is supported by frame member 15. From the above description, and consideration of parts shown in Fig. 7, it will be clear that sleeve 12 is supported at the left hand end by bearing 14—15, above described, and at the right hand end by shaft 17, which latter is supported at the right hand end by bearing 18—15, above described, and at the left hand end by and within the sleeve 12. Thus, it will be clear that sleeve 20 12, carrying worm gear 11, spur gear 13 and internal gear 19, is free to rotate either independently of shaft 17 or in unison therewith, and that shaft 17 is adapted to be propelled lengthwise within its bearing and sleeve 12 while the 25 several parts are in motion.

Referring again to the left hand end of sleeve 12, Fig. 7, also to Fig. 8, it will be noted that the body of sleeve 12 projects beyond the bearing 14—15 sufficiently to receive, in a fixed relation, an internal spur gear 19 having characteristics similar to those of spur pinion 18. Gear 19 is so affixed as to extend somewhat beyond the end of sleeve 12 the extended portion forming a toothed recess adapted to receive, in a slidable 35 manner, the pinion 18, as clearly shown in Figs. 7 and 8.

It will be clear that the combination of internal gear 19, as affixed to sleeve 12 and pinion 18 as affixed to the slideable shaft 17, form an effective clutch unit. The utility of this will be referred to presently.

Referring to the right hand end of shaft 17, Fig. 7, it will be noted that a flanged bushing 20 is affixed thereto by means of a threaded portion, as shown. A thimble member 21, having an enlarged and flanged portion, is rotatably mounted upon the bushing 20 and is retained thereon in rotatable relation by the flange of the bushing 20, washer 22 and lock-nut 22a, as clearly shown. The enlarged portion of thimble member 21 is adapted to extend somewhat over a boss portion of the frame 15 with sufficient clearance to retain a compression spring 23, which latter reacts between frame 15 and thimble 21, tending to propel shaft 17 toward the right, Fig. 7, and thus retain pinion 18 in engagement with gear 19.

Manual control of the above described clutch unit is effected through a key knob 24 conveniently located atop the mechanism housing, as shown. The key is affixed to the shank of a shouldered member 25, which latter is rotatably mounted in bushing 26 supported by the housing 16 as clearly shown in Fig. 7.

65 A perspective view of shouldered member 25 is shown in Fig. 10. It will be noted that the lower end of the enlarged portion is formed into a semi-circular lip or extension which will be referred to presently.

70 Reference to Figs. 3 and 7 will disclose a lever 27 pivotally supported upon a rounded extension of housing 16 and retained thereon by a shouldered screw 28. Lever 27 is provided with a circular opening so disposed and dimensioned as to 75 clear the body of thimble 21 already described,

and contact with the flanged portion thereof, as clearly shown in section in Fig. 7.

At its upper end lever 27 terminates in an offset portion having a circular opening so disposed as to loosely receive the body of a sleeve 5 nut 29 which is adjustably attached to a shaft 30 by means of a threaded portion, the head of nut 29 acting as a shoulder to retain lever 27, as shown. The shaft 30 is slidably mounted in a bearing 31 supported by extension from frame 10 member 15.

To the end of shaft 30 opposite the screw 29 is affixed a washer member 32, so formed and disposed that its upper side is adapted to contact with the stepped portion of rotatable member 15 25. To prevent rotation of shaft 30, the lower edge of said washer 32 is formed to complement the contour of an extended portion of housing 16 and disposed in a slidable relation with said extension, all as clearly shown in Figs. 5 and 6. 20

Consideration of Figs. 3 and 7, together with the foregoing description, will clearly indicate that spring 23, in addition to retaining clutch members 18—19 in engagement, as already described, also operates, through the flange of 25 thimble 21, lever 27, screw 29 and shaft 30, to retain washer 32 against rotatable member 25. It is also obvious that rotation of said member 25 will, due to its peculiar form already mentioned, and the follow-up action due to spring 23, impart a reciprocal motion to shaft 30, which latter is adapted, through lever 27, as already described, to impart a similar motion to shaft 17; thus, it is clear that rotation of key 24 through alternate half turns, will result in engagement 35 and disengagement of clutch members 18—19, the whole forming a convenient manual control of the ironing roller drive.

The ironing roller drive is utilized in the following manner: Considering Figs. 6 and 7, it will 40 be noted that pinion 18 is, regardless of its lateral position, in constant mesh with a spur pinion 33 fixedly mounted upon a shaft 34 which latter is rotatably mounted in bushing 35 supported by a boss extending from housing 16 as best shown in 45 Fig. 7. To the opposite end of shaft 34 is affixed a spur pinion 36 which is so disposed as to mesh with an internal gear 37 attached within the body of ironing roller tube 38.

Through the wheel and hub portion of internal 50 gear 37 and a suitable web and hub member in the outer end of tube 38, not shown, ironing roller 38 is rotatably mounted upon a tubular extension 39 which latter is rigidly supported by an extended portion of housing 16 as best shown 55 in section in Fig. 4. The roller is suitably padded with resilient material as 38a. To prevent accidental contact with moving parts, a guard plate 38b is disposed within roller 38 and affixed to housing 16, as clearly shown in Fig. 4.

60 The assembly thus far described forms a complete ironing roller drive, operable by a suitable power source through coupling 2, shaft 3, worm 10, worm gear 11, sleeve 12, internal gear 19, pinion 18, pinion 33, shaft 34, pinion 36 and internal gear 37. Control of the drive is accomplished by manual rotation of key 24 operating through member 25, washer 32, shaft 30, screw 29, lever 27, thimble 21 and shaft 17 to engage or disengage gear 18 with gear 19, as described, 65 thus controlling the linkage between the driving and driven portions of the assembly.

The ironing shoe, suitably supported and operated by means about to be described, is adapted 70 to be placed in working contact with or removed 75

from the ironing roller by manual or power means, either means being operable independently of the other. Under some working conditions, the power operated means, is used, on account of greater ease of operation. Under other conditions of ironing, the manual operation is convenient or necessary.

The shoe unit is composed of an ironing plate 40 of sufficient length to extend slightly beyond the ends of the ironing roller 38 and of suitable width to meet the requirements of manufacture and use. The contacting surface of the plate is so formed as to complement the peripheral form of roller 38, thus providing suitable contact area throughout the length of said roller 38, all as clearly shown in Figs. 2, 13, and 14.

Attached to plate 40 is a back plate 41 having a form somewhat similar to the said plate 40 and adapted to be attached thereto in such manner as to form a compartment between the two suitable for installation of necessary heating means. The heating means being of well known manufacture, will not be described.

The ironing shoe unit is supported by a bracket plate 42 rigidly attached thereto and pivotally supported by links 43 by means of a bolt 44, as shown in Figs. 2 and 15. Links 43 are pivotally supported from an arm 45 by means of a bolt 46. Arm 45 is rigidly attached to a tubular shaft 47 by means of a pin 63. The shaft will be described later.

Figs. 13, 14, and 15 will disclose arm 48 having a channel cross-section, the flanges of which are so formed at their lower ends as to include arm 45 between them. Arm 48 is supported upon shaft 47 with the bolt 46 passing through the flange portions thereof and arm 45 whereby it is substantially secured to the latter. At the upper end of arm 48 a recess is formed in the web or back portion, as 48a, said recess being adapted to receive a rearwardly extending cam portion 49a of a block 49. Block 49 is rotatably supported by bolt 44. A hand lever 50 is rigidly attached to and adapted to operate block 49. The utility of this will be explained later.

A U-shaped cradle member 51 is pivotally supported between lever members 43 by means of studs 52 as clearly shown in Fig. 15. Passing through the base portion of cradle 51, in a slideable relation, is a bolt 53, which extends through and beyond the web portion of arm 48, as shown in Figs. 13 and 14. The bolt head 58, together with a washer 57, confines a compression spring 55 against a slidable washer 56 which is backed 55 against the base portion of cradle member 51. A nut 54 backs the bolt 53 against the web portion of arm 48, as clearly shown.

It will be obvious that in the above described assembly, spring 55, through bolt head 58, bolt 53 and nut 54, as against cradle 51, and studs 52, will operate to force links 43 and 48 into a closed scissor position, this movement, however, being prevented by the locking action of cam 49a resting in recess 48a of arm 48.

The foregoing description will clearly indicate that the ironing shoe is supported by, and operable within, a complete lever system, which is supplementary to, yet supported by, the arm 48.

Under certain conditions of use, it is sometimes desirable to temporarily remove the ironing shoe from contact with the roller 38 without disturbing the position of the major operating members.

The above described assembly provides manual means for effecting such removal. The dotted

outline shown in Fig. 13 clearly indicates the action.

When hand lever 50 is rotated toward the dotted line position, cam 49a is removed from its locked position in recess 48a, permitting spring 55 to operate links 43, as described, thus withdrawing the ironing shoe as clearly outlined in the drawings. It will be noted that arm 48 remains stationary during this operation. Return of the operating handle to its normal position 10 reestablishes original relative positioning of the several members.

Manual operation of the ironing shoe having been described, power operation will next be considered.

As indicated in Fig. 2, the ironing shoe unit is rigidly supported by an outboard stand 59, which is attached to table 61, as shown, and connected with housing 16 by a structural tube 60. The tubular shaft 47 is rotatably supported at its outboard end by a suitable bearing located within tube 60, and at its driven end by a bearing formed in the body of housing 16. The tube 60 forms an effective cover for the moving shaft, as well as structural strength for the several parts mentioned.

As already mentioned, arm 45 is rigidly affixed to the tubular shaft 47, a plug 62 serving as reinforcement for the walls of the tube and body of pin 63 as shown.

To the opposite end of shaft 47, within the housing 16, a double arm 64 is rigidly attached by means similar to those described in the case of arm 48. Rotatably mounted between the members of arm 64 is a trunnioned block 65, in the central portion of which a stud 66 is affixed by means of thread and set screw as shown. The opposite end of stud 66 is provided with an adjustable nut 67 and washer 68, which will be referred to again shortly.

Figs. 3, 7, etc. will disclose a double armed lever 69, the arms of which are so disposed as to be rotatably supported by shaft 47 and to include arms 64 between them. Structurally, the two side members composing the lever 69 are 45 rigidly joined to function as a unit by means of a connecting portion as 73, a shouldered collar 70 and beaded bushing 71, together with a shouldered rivet 72, as shown.

Referring again to stud 66, etc., it will be noted that a compression spring 74 is confined upon stud 66 between connecting portion 73 of lever 69 and washer and nut 68-67. The function of the above described assembly is to provide a resilient coupling between shaft 47 and lever 69, operating through arm 64, block 65, stud 66, nut 67, spring 74, to lever 69 through connecting portion 73. The assembly is best shown in Fig. 3.

Pivotedly attached to the extremity of lever 60 69 by means of a pin 75, is a link member 76, the opposite end of which is enlarged and flanged to form a suitable band for rotatable operation upon an eccentric member 77, as clearly shown in Figs. 3 and 4. Link member 76 is also provided with an extended lip portion 78, as shown in detail in Fig. 16. The function of this will be explained later.

Considering the foregoing description, together with the figures noted therein, it will be clear 70 that rotation of eccentric 77 will result in a reciprocal motion in lever 69 through link 76, and that a similar motion will be imparted to ironing shoe 40 through lever 69, spring 74, etc., to arm 64, through shaft 47 to arm 48 and shoe 40. 75

Thus, the function of eccentric 77 is to apply and remove the ironing shoe to and from contact with the ironing roller 40. The resilient mechanism, including spring 74, stud 66, etc., are so adjusted that the angular movement of lever 69 is somewhat greater than that of ironing shoe 40. The result of this adjustment is that shoe 40 contacts with the face of the ironing roller somewhat before lever 69 reaches the limit of its stroke to the left, as viewed in Fig. 3. Continued rotation of eccentric 77 toward the left results in continued motion of lever 69 and consequent compression of spring 74, the pressure induced thereby being transmitted to shoe 40 by means already described. Thus, the contact pressure between shoe and roller is firm but yielding, and may be adjusted by means of nut 67 on stud 66.

Integral with the body of eccentric 77 is a disk portion 79, the whole being rotatably supported by a shouldered stud 80 which is affixed in the plug 81, the latter being pressed into tube 39, all as shown in Fig. 4. The outer end of stud 80 is supported by a bracket member 92 disposed and attached to housing member 16, as best shown in Fig. 3.

Motion is imparted to eccentric 77 through a clutch coupling to be described, and a spur gear 94, which latter is meshed with power driven gear 13 affixed to sleeve 12, as already noted and described.

Fig. 4 will indicate that gear 94 is rotatably supported upon stud 80, already described. A toothed disk member 93 is fixedly attached to gear 94 by means of a boss extension of the hub of the latter and riveted pins, as clearly shown in section in Fig. 4. The unit is adapted to idle freely upon stud 80. An outline of disk 93 is clearly shown in Fig. 5.

It has already been noted that integral with the body of eccentric 77 is a disk portion 79 so disposed that its face opposes the side face of toothed disk 93 as clearly shown in Fig. 4. The face of disk 79 is recessed to several levels, the level, area and form of the recesses being suitable to receive operating members to be described.

Referring to Figs. 11 and 12, the areas designated as 79c correspond to the face of disk 79, while 79b designates a recessed area of what might be called single depth with similar area located on the opposite side, and 79a designates an area of double depth.

Rotatably retained in recess 79a is a plate member 82 having a central circular opening, as shown, also diametrically opposed projecting finger members as 82a and 82b and a rigidly affixed stud 90, disposed as shown and projecting outwardly from the surface of the plate 82.

Slidably retained upon the areas 79b is a plate member 83 having a recess 91 formed in its upper edge dimensioned and disposed to loosely receive stud 90, also an oblong opening dimensioned and disposed to clear the hub portion of disk 79, as shown. Rigidly affixed to the surface of plate 83 is a block part 84 disposed and formed as shown with a tooth 84a projecting toward the center and extending outwardly from the surface of the plate.

Plates 82 and 83 are of such thickness as to approximately complement the depth of recess which they occupy. In assembly, plate 82 is rotatably retained in the double depth recess 79a by plate 83, the same resting upon a higher level, while plate 83 is slidably retained in the single depth recesses 79b by four washers 86 af-

fixed to the disk surface level by rivets 87 as shown.

It will be clear that fractional rotation of plate 82 with relation to the body of disk 79, will result in a corresponding reciprocal motion of plate 83 through stud 90 operating in recess 91. Rotation of plate 82 beyond predetermined limits is prevented by shoulders formed by the raised areas 79c.

The relative positions of disk 79 and toothed disk 93, as assembled upon stud 80 has already been noted. Considering the foregoing description, it will be clear that with the parts assembled as described, the toothed block 84, projecting beyond the surface of plate 83 and disk 79, will also project over toothed disk 93 as shown in Fig. 4. A plan view of the several parts is clearly shown in Fig. 5, also a broken section of toothed disk 93 is outlined in Figs. 11 and 12.

It has already been noted in connection with Figs. 5 and 7, that a spur gear 13 is fixedly mounted upon the power driven sleeve 12. The view shown in Fig. 5 illustrates that gear 13 runs in mesh with gear 94, thereby gear 94, together with toothed disk 93 is maintained in rotation by the power source.

Considering the foregoing, in connection with Fig. 11, it will be obvious that rotation of plate 82, with relation to disk member 79 will, by means already described, result in movement of tooth 84a toward center and into engagement with toothed disk 93. Assuming that disk 93 is in rotation when said engagement takes place, it is clear that eccentric 77 will be set in motion through members already described.

Still referring to Fig. 11, it will be noted that tooth 84a is normally retained in engagement with disk 93 by the action of a spring 88 attached to plate 82 by means of a stud 89 and to disk 79 by one of the rivets 87 as clearly shown.

Assuming disk 93 to be in rotation in direction shown by the arrow and the parts positioned as shown in Fig. 11, it is obvious that disk 79 will be rotated through engagement between disk 93 and tooth 84a, until finger 82a meets an obstruction such as stop 95. Continued rotation of the unit, with rotation of plate 82 arrested by stop 95, will displace the parts as shown in Fig. 12, wherein plate 83 has been displaced toward the right by means already shown and described and tooth 84a has been withdrawn from engagement with disk 93. With the parts positioned as shown in Fig. 12, it is clear that, while disk 93 continues to rotate, disk 79 will remain stationary until stop 95 is removed to a non-obstructive position. When such removal takes place, spring 88 will restore parts to the relative positions shown in Fig. 11. It is considered obvious that if, after each escapement of fingers 82a or 82b, stop 95 is restored to the obstructive position, rotation 60 cannot continue beyond one hundred and eighty degrees without further manipulation of the stop.

Bearing in mind that eccentric 77 is integral with disk 79, it is apparent that intermittent rotation of disk 79 in steps of one hundred and eighty degrees, will result in a like movement of eccentric 77.

Referring to Fig. 3 and assuming that with the clutch members positioned as shown in Fig. 12, eccentric 77 is in the position shown in Fig. 3, it is clear that removal of stop 95, as already noted, will result in rotation of eccentric 77 to a stop one hundred and eighty degrees from the original position, the latter movement resulting in described movement of lever 69 and associated 75

parts to place the ironing shoe in contact with the roller through means already described.

It will be apparent that a further momentary removal of the stop 95 will result in rotation of eccentric 77 through another half revolution or to a position diametrically opposite that shown in Fig. 3, causing the ironing shoe to return to contact with the ironing roller.

Manual control of the above described clutch unit is effected through operation of the stop 95 as already noted. Reference to Fig. 4 will show that stop 95 is fixedly attached to a shaft 96 which is rotatably mounted in suitable bearings and disposed at right angles to stud 80. Shaft 96 passes through the wall of housing 16 and terminates in a knob 97 by which the shaft is conveniently rotated as desired.

Rotation of shaft 96 is limited by extensions 98 and 99 which are integral with the body of stop 95 and provided with resilient facings as 100 and 101.

A coil spring 102 suitably attached to shaft 96 and body of housing 16 tends to rotate said shaft 96 in a clockwise direction, as viewed in Fig. 4, thus maintaining extension 99 in contact with housing 16 and stop 95 in position to obstruct fingers 82a or 82b.

It is obvious that slight manual rotation of knob 97 in counterclockwise direction will result in similar movement of stop 95 out of line of obstruction to teeth 82a and 82b, thus permitting operation of the clutch unit as already described. Practical manipulation of the knob would consist of a slight rotation counter-clockwise, and release. This manipulation would obviously remove stop 95 out of line of tooth 82a or 82b, allowing same to escape. Release of the knob would result in restoration of stop 95 to its original position, ready to obstruct the next approaching tooth as 82a or 82b. Thus, each manipulation of the knob 97 would result in a half revolution cycle of operation as described, with resultant operation of the ironing shoe also described.

Mention has already been made of an extended lip portion 78 as integral with link 76. Referring to Fig. 16, it will be noted that the said lip is so disposed upon link 76 that when the link passes through the upper swing of its cycle, the lip 78 contacts with a shoulder formed in the body of lever 27, as clearly shown in Fig. 16. The result of this contact is a displacement of lever 27 to disengage the roller operating clutch by means already described.

The movement of lever 27 is identical with that produced by manipulation of the key 24, already described. Since the ironing shoe is thrown out of contact by the upper swing cycle of link 76, it follows that whenever the ironing shoe is, by power, thrown out of contact, rotation of the ironing roller is automatically stopped.

Obviously, when the ironing shoe is reapplied as a result of a succeeding manipulation of the knob 97, the accompanying lower and backward swing of link 76 will result in withdrawal of the lip 78 from contact with lever 27, allowing gears 18-19 to reengage and resume rotation of the ironing roller. Thus, rotation of the ironing roller is automatically started and stopped as the ironing shoe is applied or withdrawn by the power means.

In order to provide lubrication for the mechanism, a pump 103 is attached to housing 16 as shown in Fig. 3. The plunger 104, the upper end 75 of which terminates in a button-like head 105,

is so positioned as to contact with the lower edge of link 76 as shown in Figs. 3 and 9. Plunger 104, shown in section in Fig. 9, is normally held in an out-stroke position by a spring 106, and is adapted to be forced downwardly and in by the lower edge of link 76 as the latter moves through the lower swing of its cycle. As clearly shown in Figs. 3 and 9, pumping movement is imparted to plunger 104 by the alternate action of spring 106 and cam-like action of link 76. Oil is taken in through an orifice 107, checked by a ball 108, forced through check 109, through tube 110 and ejected therefrom so as to fall upon the mechanism. Oil is supplied to the pump from a reservoir formed in the lower part of housing 16, where it returns for recirculation after flowing over the mechanism.

From the foregoing description, it will be clear that ample lubrication is provided as a consequence of the frequent operation of the ironing shoe unit.

It is well known that ironing machines of the class described are used for ironing a great variety of materials and garments. Obviously, to explain the operation of the machine with reference to each material or garment would involve almost endless detail.

It is thought that operation of the several parts and groups composing this ironer have already been described with sufficient detail to obviate the need for any but summary description herein.

It will be noted that the ironer has several distinct means of manipulation, first the individual control of rotation of the ironing roller by means brought into operation by manipulation of the key 24, second, individual operation of the ironing shoe by manipulation of the hand lever 50 and, third, control of power operation of the ironing shoe and roller by manipulation of the knob 97.

The combination of the three operating features mentioned obviously adapts the machine to a wide variety of uses, which may be summarized as follows:

With motor running and the several parts of the mechanism in rotation as described and with the ironing shoe in non-working position, the operator places material to be ironed upon the ironing roller in such a position that the entering edge of the material will be under the ironing shoe when the shoe is brought into contact with the roller. A slight turn of the knob 97 will cause the shoe to move forward into contact with the roller and material, following which a half turn of key 24 will set the roller in motion. Thus, the material will be inducted under the ironing shoe and properly pressed.

It might be noted here that in the above case, if key 24 had been in running position, the ironing roller would have started rotation simultaneously with inward movement of the ironing shoe by means previously described.

With the roller in motion and the shoe in contact, materials of ordinary thickness may be continuously fed over the roller and under the shoe.

When ironing certain thick materials, such as folded blankets, which might not easily enter under the shoe, it may be desired to stop the roller temporarily, which is accomplished by rotating key 24 one half turn. In order to properly adjust materials under the ironing shoe, the shoe may be temporarily raised by operation of hand lever 50 as described. When the material is adjusted, the shoe may be replaced by return of the hand lever to its original position, after

which the roller may be restarted by another half turn of key 24.

In case the material being ironed includes buttons or other projecting portions, the ironing shoe 5 may conveniently be adjusted by hand lever 58 to assist the passage of the irregular portions.

In cases where the particular work being done requires simple pressure of the heated shoe rather than frictional or rubbing contact as provided by 10 a revolving roller, the ironing shoe may be applied to the roller by manipulation of the knob 97 as described, while the roller is made stationary by manipulation of the key 24, also as described. With the roller stationary and the ironing shoe in the applied position, the shoe may be 15 withdrawn by manipulation of the hand lever 58, as described. With the shoe in this position, the material may be arranged upon the stationary roller after which the shoe may be applied by 20 return of hand lever 58 to an upright position. The shoe may be withdrawn and reapplied at will. Obviously, this class of work may be performed with the operating motor shut off.

Usual operation of the ironer may be resumed 25 by re-starting the motor, in case it has been shut off, and manipulating the several controls as described.

In case it is desired to iron tubular garments, such as skirts, it is necessary to stop rotation of 30 the roller and remove the ironing shoe to permit adjustment of the garment over the roller. This is accomplished by manipulation of the knob 97 as described, to remove the shoe and stop the roller. After the garment has been adjusted, another manipulation of the knob will result in re- 35 placement of the shoe and rotation of the roller. In case the garment is of intricate pattern, proper adjustment of it may be assisted by manipulation of the hand lever 58, as required, also rotation of 40 the ironing roller may be conveniently controlled by manipulation of the key 24 as described.

It is thought that the foregoing will illustrate the adaptability and convenience of this new combination.

45 What I claim is:

1. In an ironing machine of the class described, in combination, an ironing roller, manually operated means for controlling rotation thereof, an

associated ironing shoe, power driven means for the operation thereof including a clutch, an associated eccentric member, a link member adapted to transmit motion from the said eccentric to the shoe operating mechanism, manually operated means for controlling operation of said clutch to impart rotation to said eccentric and motion to said link, and means integral with said link to engage and operate a member of the manually operated roller drive clutching means to discontinue rotation of the roller when the ironing shoe operating means is operated to remove the shoe from contact with the roller.

2. In an ironing machine of the class described, in combination, an ironing roller, manually operated means for controlling rotation thereof, an associated ironing shoe, power driven means for the operation thereof including a clutch, an associated eccentric member, a link member adapted to transmit motion from said eccentric to the shoe 15 operating mechanism, manually operated means for controlling operation of said clutch to impart rotation to said eccentric and motion to said link and a projecting part on said link adapted to engage and operate a member of the manually 20 operated roller drive clutching means to discontinue rotation of the roller when the ironing shoe 25 operating means is operated to remove the shoe from contact with the roller.

3. In an ironing machine of the class described 30 in combination, an ironing roller, manually operated mechanism for controlling rotation thereof, an associated ironing shoe, power driven means for the operation thereof including a clutch, an associated eccentric member, a link member 35 adapted to transmit motion from said eccentric to the shoe operating mechanism, manually operated means for controlling operation of said clutch to impart rotation to said eccentric and motion to said link, a projecting part on said link, 40 said manually operated roll control mechanism having a part lying in the path of said projecting part and being engageable and movable thereby during movement of said link to actuate the roll control mechanism to stop the roll when the 45 link is operated to move the shoe away from the roll.

JOHN A. CASTRICONE.
